CLAIM

The ornamental design for an agitator on a straw or rod for a shakable container, as shown and described.

DESCRIPTION

FIG. 1 is a front perspective view of an agitator on a straw or rod for a shakable container according to the present invention;

FIG. 2 is a front view of the agitator on a straw or rod for a shakable container as shown in FIG. 1;

FIG. 3 is a rear view of the agitator on a straw or rod for a shakable container as shown in FIG. 1;

FIG. 4 is a first side view of the agitator on a straw or rod for a shakable container as shown in FIG. 1;

FIG. 5 is a second, opposite side view of the agitator on a straw or rod for a shakable container as shown in FIG. 1;

FIG. 6 is a top plan view of the agitator on a straw or rod for a shakable container as shown in FIG. 1;

FIG. 7 is a bottom view of the agitator on a straw or rod for a shakable container as shown in FIG. 1; and,

FIG. 8 is an exploded view of the agitator on a straw or rod for a shakable container as shown in FIG. 1; the agitator, straw or rod, and lid may be friction fitted to one another, and in particular the agitator may be friction fitted anywhere along the straw or rod, as desired.

Any broken lines shown are directed to environmental structure and are for illustrative purposes only. Such broken lines form no part of the claimed design.
